UNITED STATES PATENT OFFICE.

ALBERT E. PAGE, OF BROOKLYN, NEW YORK, ASSIGNOR TO SCOTT AND WILLIAMS, INC., OF NEW YORK, N. Y., A CORPORATION OF MASSACHUSETTS.

TUCKING ATTACHMENT FOR KNITTING-MACHINES.

1,367,425.

Specification of Letters Patent.

Patented Feb. 1, 1921.

Application filed April 24, 1920. Serial No. 376,211.

To all whom it may concern:

Be it known that I, ALBERT E. PAGE, a citizen of the United States of America, residing in Flatbush, in the borough of Brooklyn, in the county of Kings and State of New York, have invented a certain new and Improved Tucking Attachment for Knitting-Machines, of which the following is a specification.

10 My invention consists of an improved tucking attachment for knitting machines, more particularly adapted for use in the production of the fashioned seamless stocking which forms the subject of the Scott 15 Patent No. 1,233,714, dated July 17, 1917. Said patent shows a seamless stocking having at the back of the leg two rows of distinguishing marks, which are preferably formed by tuck stitches, that is, loops held 20 up in given wales and courses.

A convenient means for producing tuck stitches is that disclosed in the Brown Patent 642,579, February 6, 1900, and comprising the provision of needles with longer 25 latches for knitting those wales in which the tuck stitches are to be produced than in the case of the needles for the wales in which no tuck stitches are to be made, and in connection therewith is provided a movable clearing cam and mechanism to operate the cam so that at some courses all the needles will be moved to clear the stitches and at other times the needles will be projected only far enough to clear the stitches 30 on the short latch needles, and not those on the long latch needles. In the accompanying drawings I have shown a tuck-producing means of this type for illustration of my invention, but I do not limit myself to 35 that type of tuck-producing means.

According to my present invention, the clearing cam is set to the tucking position by means of the pattern chain and a tripping means operated from some moving 45 part of the machine causes the clearing cam to return to the plain knitting position, at the proper time. Thereby I am enabled to secure appropriate timing from slow moving parts of the machine.

50 In the accompanying drawings I have shown my improved tucking machine for application to one of the well known Scott and Williams machines, employing a rotating needle cylinder and stationary cam cylinder.

Figure 1 is a side elevation illustrating the main elements of my invention;

Fig. 2 is a front view of the same;

Fig. 3 is a plan view;

Fig. 4 is a view of the stitch cams; 60

Fig. 5 illustrates long and short latch needles.

In the case illustrated I have shown the leading stitch cam 50 as the movable clearing cam, pivoting it at 51 and providing its 65 free end with a pin 52, projecting to the exterior of the cam cylinder. This pin 52 as seen in Fig. 3, rests upon the outer end of a lever 49, pivoted at 48 to a suitable bracket on the bed plate 10' of the machine and connected at the other end to an upright rod 19. The lower end of this rod 19 has a pin and slot connection at 11, 12 with the arm 10 of a bracket 3, which is pivoted on the horizontal shaft 2 and is 70 under the control of the pattern chain 8 through the medium of an arm 6 on the bracket having an adjustable pin 7 overlying the pattern chain.

To the lower end of the rod 19 is pivoted 80 a latch 14, whose catch 15 engages the upper side of the arm 10, as seen in Fig. 1, when the pin 11 on the arm 10 is at the bottom of the slot 12 in the rod 19. A spring 13 (Fig. 1) tends to draw and thus hold 85 the latch in engagement with the end of the arm 10, and it also tends to draw down the rod 19 and lift the clearing cam. When a lug 9 on the pattern chain comes into contact with the pin 7, it rocks the bracket 3 90 on its pivot with the result that the rod 19 is lifted, and the clearing cam 50 thereupon dropped to the position shown by dotted lines in Fig. 4, where the long latch needles will no longer clear their stitches, and tucks 95 will be produced so long as the rod 19 remains elevated. But since the pattern chain is relatively slow moving and it is undesirable to tuck more than two successive

100 stitches, I provide means for automatically tripping the rod 19 and allowing it to drop, so as to thereby raise the clearing cam 50 to the clearing position for all the needles while the bracket 3 is still held in its tilted position with its pin 7 on the lug 9 of the 105 pattern chain.

This tripping mechanism consists of a push rod 23 pivoted at 24 to the usual rocking quadrant 22, which rocks on the axis 25 and also has pivoted to it at 21 the feed 110

pawl 20 for imparting feed motion as usual to the pattern chain wheel.

The free end of the push rod 23 slides to and fro in a notch in the bracket 3, and as it is pushed to the right, Fig. 1, on the rocking of the quadrant 22, it strikes against the end 29 of a wire 28 carried by the arm 27, (Fig. 2) on the pivoted latch 14, disengaging the latter from the arm 10. If at 10 the moment the bar 29 is in the elevated position indicated in Fig. 1, this bar will thereupon drop, and the clearing cam 50 will rise and the tucking cease. The points of pivotal connection of the feed pawl 20 and 15 the tripping rod 23 to the quadrant 22 are such that for the most part the two move in opposite directions, and the tripping rod has a longer movement than does the feed pawl. This tripping of the cam-controlling 20 rod 19 is timed to take place so that the clearing cam will be returned to its full clearing position on or before the completion of two revolutions.

When therefore the pin 7 of the bracket 25 3 drops off the lug 9, so that the bracket 3 swings back to its normal position shown in Fig. 1, the pin 11 on the arm 10 will drop back again to the bottom of the slot 12 in the bar 19 and thereupon the pivoted latch 14 30 will reengage the arm 10, as shown. Plain knitting will continue until another lug 9 on the pattern chain comes along to rock the swinging bracket 3 and thereby raise the bar 13 and so lower the clearing cam 50 for tucking.

I claim as my invention:—

1. A knitting machine having needles some of which are adapted to be used for tucking and a movable clearing cam therefor in combination with a pattern mechanism and devices operated by the pattern mechanism to move said cam to the tucking position and a tripping means operated from a moving part of the knitting machine 40 to cause the clearing cam to return to the plain knitting position.

2. A knitting machine having needles

some of which are adapted to be used for tucking and a movable clearing cam therefor in combination with a pattern mechanism and devices operated by the pattern mechanism to move said cam to the tucking position and a tripping means operated from a moving part of the machine to trip 50 said cam controlling devices, for the purpose set forth.

3. A knitting machine having needles some of which are adapted to be used for tucking and a movable clearing cam therefor in combination with a pattern mechanism and devices operated by the pattern mechanism to move said cam to the tucking position, a rocking arm, a feed pawl for the pattern mechanism operated by the latter, and a trip rod also operated by said rocking 60 arm to trip the cam controlling devices.

4. A knitting machine having needles some of which are adapted to be used for tucking and a movable clearing cam therefor in combination with a pattern mechanism, a pivoted bracket adapted to be operated by the pattern mechanism, a bar having a pin and slot connection with said bracket and controlling the position of the clearing cam, a holding latch for the pin and 70 slot connection and means for tripping said latch.

5. A knitting machine having needles some of which are adapted to be used for tucking and a movable clearing cam therefor in combination with a pattern mechanism, a pivoted bracket adapted to be operated by the pattern mechanism, a bar having a pin and slot connection with said bracket and controlling the position of the clearing cam, a holding latch for the pin and slot connection, a trip bar for the latch, 80 a rocking quadrant to which the trip bar is pivoted and a feed pawl for the pattern mechanism, also pivoted to said quadrant. 85

In testimony whereof I have signed my name to this specification.

ALBERT E. PAGE.
